UNITED STATES PATENT OFFICE.

RUTH S. HAWKINS, OF EUGENE, OREGON.

SHOE-FITTING DEVICE.

Application filed January 21, 1926. Serial No. 82,825.

This invention relates to a shoe fitting device and more particularly to a device for determining whether a shoe made upon a given last properly fits the foot of the would-be purchaser.

An important object of the invention is to provide a device of this character which permits observation of the toes of the foot while positioned upon the foot so that it may be determined whether a shoe of that particular size and shape will provide proper room for the toes.

A further object of the invention is to provide a device of this character which may be secured upon the foot so that the wearer might stand and determine whether or not the toes move too far to the front of the shoe when weight is applied thereto and when he steps with the shoe in position upon his foot.

20 A further object of the invention is to provide a device of this character which may be very readily and cheaply produced and which will be durable and efficient in service.

These and other objects I attain by the construction shown in the accompanying drawing, wherein for the purpose of illustration is shown a preferred embodiment of my invention and wherein:

Figure 1 is a perspective view of a shoe fitting device constructed in accordance with my invention;

Figure 2 is a perspective of the sole element removed;

Figure 3 is a perspective of the tip element removed.

Referring now more particularly to the drawings, the shoe includes a base or sole section 10 having a portion 11 for engaging and limiting rearward movement of the foot within the shoe. The portion 11 is preferably provided with straps or similar expedients, as indicated at 12, whereby it may be secured about the instep to hold the base in position upon the foot. To this base is applied a false sole 13 which is preferably of paper having its under surface gummed. Arising from this false sole is a tip portion 14 having opaque and transparent portions 15 and 16, the opaque portions 15 having upon their outer faces adhesive whereby they may be secured to the forward edges of the portions

11. The transparent portion 16 must extend at least to the base of the toes but may be extended to the instep, as indicated in the present illustration. The under surface of the false sole 13 is secured to the sole 10 in any suitable manner as by applying to the under surface of this false sole a layer of adhesive. Any suitable means may, however, be provided for securing the tip section 14 to the sole 10. The construction illustrated is preferable for the reason that it permits ready removal of the tip in event of damage thereto so that it may be replaced. The transparent section 16 may be of isinglass or other suitable material.

Since the construction hereinbefore described is obviously capable of a certain range of change and modification without materially departing from the spirit of the invention, I do not limit myself to such specific structure except as hereinafter claimed.

I claim:

1. In a shoe fitting device, a sole element having at its rear end means for limiting rearward movement of the foot thereon and having means whereby it may be secured in position upon the foot of the wearer and a toe structure secured to said sole element and having a transparent portion exposing to view the toes of the wearer when the device is in applied position upon the foot, said toe structure having attached thereto a false sole, said false sole being removably attached to said sole element.

2. In a shoe fitting device, a sole element having at its rear end means for limiting rearward movement of the foot thereon and having means whereby it may be secured in position upon the foot of the wearer and a toe structure secured to said sole element and having a transparent portion exposing to view the toes of the wearer when the device is in applied position upon the foot, said toe structure having attached thereto a false sole the undersurface of which has applied thereto an adhesive element to permit its attachment to the sole element.

In testimony whereof I hereunto affix my signature.

RUTH S. HAWKINS.
